PACKAGING MACHINE

Ross T. Adams, Richard S. Poole, and Morris Raymer, Battle Creek, Mich., assignors to Kellogg Company, Battle Creek, Mich., a corporation of Michigan

Application June 8, 1932, Serial No. 616,007

31 Claims. (Cl. 93—6)

This invention relates to packaging machines and more particularly to machines of that character adapted to seal the mouth of a material containing bag by the application of adhesive thereto.

5 An object of the invention is the provision of automatic means for applying adhesive to the mouth of a bag to be sealed.

Another object is the provision of automatic 10 means for applying adhesive to the mouth of a bag disposed within a protective carton.

A further object is the provision of automatic means for applying adhesive to the mouth of a bag while the latter is moving.

15 A still further object is the provision of adhesive applying means adapted to apply adhesive to each of a plurality of moving bags successively while traveling with the same.

Still another object is the provision of means 20 for replenishing the adhesive on the adhesive applying mechanism between each successive application of adhesive and while the said mechanism is moving to position to operate upon another bag.

25 Other objects more or less incidental and ancillary to the foregoing will appear in the following description and claims.

While the present invention is adapted for use in sealing any type of bag and in combination with various types of machines, it is especially adapted to seal the conventional inner liner (bag) of a cereal carton. Moisture affects adversely most cereal foods. It is, therefore, desirable to store such cereals in moisture proof packages or containers. Heretofore cereal packages have been moisture-proofed by enclosing them in an outer covering impervious to moisture. More recently the outer covering has been dispensed with and the inner liner (bag) has been formed of moisture proof paper, usually a wax impregnated paper. After a bag of this kind has been filled with the desired cereal it is necessary to close and seal the mouth thereof. In the past this sealing of the mouth has been accomplished in automatic machines by either of two methods: namely, by forming suitable folds in the extended portion of the mouth or by pressing this portion of the mouth together while applying heat thereto whereby to melt the wax contained in the paper sufficiently to cause adherence of the adjacent surfaces.

However, in some respects neither of these methods of closing and sealing a bag have been entirely satisfactory. In the case of a seal formed 55 by folding the mouth of the bag, a slight dis-

turbance or derangement of the bag causes the fold to become unfolded sufficiently to permit the ingress of moisture laden air into the bag. In the case of the wax seal, difficulty is experienced in providing a proper amount of wax in the paper and regulating the application of heat so as not to melt the wax to so great an extent that it flows away from the portion of the bag to be sealed.

Both of the foregoing methods have been used 10 in automatic machinery and carried out while the bag to be sealed is moving continuously and usually after it has been inserted in a protective carton.

The present invention is designed to provide a 15 seal which is not subject to the defects inherent in the prior art seals, and which may be applied to a bag contained within a carton while the same is being moved continuously. It is contemplated that the present invention will be embodied 20 in a unitary machine designed merely to seal a bag or in a machine adapted to perform various other operations in addition to the sealing of a bag. This invention accordingly comprises the features of construction, combination 25 of elements and arrangement of parts herein-after described and claimed.

A machine illustrating one embodiment of the present invention is shown in the accompanying drawings, in which:

30 Figure I is a side view in elevation of the complete packaging machine embodying the present invention.

Figure II is an enlarged top plan view of a portion of the machine shown in Figure I.

35 Figure III is an enlarged partial top plan view of the packaging machine shown in Figure I illustrating the details of construction of the bag sealing mechanism.

Figure IV is an enlarged partial side view in 40 elevation of the packaging machine shown in Figure I in which the details of the bag sealing mechanism are shown.

Figure V is an end elevation of the structure 45 shown in Figure IV with parts broken away.

Figure VI is a partial sectional view of the structure shown in Figure V taken on substantially the line VI—VI of that figure and showing the adhesive applying carriage mechanism in the opposite position to that shown in Figure V.

50 Figure VII is a partial plan view of the structure illustrated in Figure III showing the adhesive applying carriage mechanism in center position.

Figure VIII is a cross-sectional view taken on 55

substantially the line VIII—VIII of Figure III illustrating the mechanism for moving the adhesive applying carriage mechanism.

Figure IX is an enlarged partial plan view of the structure shown in Figure I.

Figure X is a diagrammatic plan view of the driving mechanism for the packaging machine embodying the present invention; and

Figure XI is a side view in elevation of the driving mechanism shown in Figure X.

The machine herein shown and described is substantially identical in many details of its construction and operation to the machine shown in United States Letters Patent No. 1,824,401, issued September 22, 1931. It is adapted to receive open mouthed material containing bags disposed within open topped protective cartons and to operate upon the same to (1) prepare the carton, the bag, and the contents of the bag for the subsequent closing and sealing operations; (2) seal the mouth of the bag and tuck it into the carton; (3) close the top of the carton over the bag and expel the closed package from the machine.

For the sake of convenience and clarity, the following description of the construction and operation of the machine is divided into three chapters corresponding to these three operations.

CHAPTER I

30   *Carton and bag preparing mechanism*

As shown in Figures I and II packages P comprising open mouthed material containing bags disposed within open topped protective cartons may be delivered to the packaging machine embodying this invention by means of an endless carrier belt 20. The outer extremity of the carrier belt 20 may be supported upon a conventional pulley member, not shown, and is supported at its inner extremity by means of a driving pulley 21. The pulley 21 is secured to a shaft 23 which is rotated by means of a chain 22 passing over a suitable gear carried by a shaft 23 and a similar gear carried by drive shaft 24.

A pair of guide rails 25 and 26 are secured to the machine frame and disposed slightly above and to the sides of the carrier belt 20 where they serve to position the packages P upon the belt. The guide rails 25 and 26 are provided with a pair of staggered off-set portions 27 arranged so that the movement of a package transported by the carrier belt 20 will be interrupted upon the package arriving adjacent these portions.

Suitable projecting mechanism including a plunger 19 is located adjacent each of the off-set portions 27. The plungers 19 are pivotally connected to the upper extremity of bell crank levers 18 which are in turn pivotally mounted on the machine frame at 17. The levers 18 carry rollers 16 at their lower extremities. Forks 15 rigidly connected to a shaft 14 engage the rollers 16. Shaft 14 is oscillated by means of a pitman, not shown, operatively associated through a suitable cam with shaft 24. The oscillation of shaft 14 causes forks 15 to actuate bell crank levers 18. The plungers 19 are thus operated to project the packages past the off-set portions 27 at proper intervals whereby to properly space them upon the carrier belt 20. While the packages are restrained by the second off-set portion 27 the contents of the package are tamped into position by means of a tamping block 28 actuated by reason of a driving connection with the drive shaft 24. As soon as the tamping operation is completed the second plunger 19 is projected and the

package permitted to pass the second off-set portion 27.

Immediately thereafter the package comes in contact with a stop 29, at which point it is transferred from the carrier belt 20 to an individual carrier member 31 by means of a plunger 30 also operatively connected to the drive shaft 24. The individual carrier member 31 consists of a base or carrier plate 32 secured to a standard 33 and is movably positioned upon a guide rail 34. The carrier is moved along the guide rail 34 by means of an endless chain 35 which passes over sprocket gears 36 carried by the drive shaft 24 and a similar shaft 37. The carrier members 31 are suitably spaced apart by reason of their connection to the endless chain 35, and the movement of the chain 35 is suitably timed, to permit subsequent operation upon the package as hereinafter described.

The package is next operated upon by mechanism adapted to spread the mouth of the bag and to press the side flaps of the carton downwardly, whereupon they are engaged by flap retaining rails. At the same time the forward carton flap is deflected from its normal vertical position to a position where it is subsequently engaged by a forward flap bending finger.

This mouth spreading and flap deflecting mechanism comprises a bracket 38 carrying a pair of spreader plates 39 and a front flap deflecting arm 47. The bracket 38 is rigidly secured to a rotating shaft 40. The shaft 40 is rotated by means of a suitable driving connection with the drive shaft 24.

The spreader plates 39 are pivotally connected to an extension of bracket 38 at their inner extremities and are normally held in an inoperative position by reason of their connection with a bell crank lever 13 pivotally mounted on bracket 38 at 12. One end of lever 13 is pivotally connected to an arm, not shown, which is in turn pivotally connected to spreader plates 39. A roller 41 is mounted on the other end of lever 13.

As the shaft 40 rotates roller 41 contacts a stationary cam 42 having an offset which at the proper time deflects the lever 13 and causes the spreader plates 39 to press the mouth of the bag and the side flaps of the carton downwardly.

During the mouth spreading and flap deflecting operation the package is held against lateral movement by means of a pair of guide rails 43 and 44, secured to which and positioned immediately above the same are a pair of side flap retaining rails 45 and 46 which engage the flaps as they are pressed downwardly by the spreader plates 39 and thereafter retain the flaps in that position until they are released as hereinafter described. While the spreader plates 39 are spreading the mouth of the bag apart and deflecting the side flaps of the carton the front flap deflecting arm 47 is pressing the forward flap of the carton away from the mouth of the bag.

Before the forward flap of the carton is released by the finger 47 that flap is engaged by another arm 48 carried at the extremity of a rotating shaft 49 which is driven from the shaft 40 by means of a drive chain 50. The travel of arm 48 is shown in dotted lines in Figure IV. The arm 48 presses the forward flap of the carton to a position somewhat below horizontal. While the flap is retained in this position a flap retaining plate 51 secured to the next preceding carrier member 31 is actuated to engage the flap and thereafter retain it in a substantially horizontal position. The flap retaining plate 51 is

normally held in an inoperative position by suitable resilient means and is actuated to engage the flap at the proper instant by means of an arm 52, as shown in Fig. V, operatively connected to the plate 51, striking a stationary stop 53 secured to the bed of the machine. The stop 53 continues to hold the flap retaining plate 51 in its operative position until the flap is released in order to close the carton as hereinafter 10 described.

CHAPTER II

Bag sealing and tucking mechanism

It will be remembered that the side flaps and forward flap of the carton are retained in position away from the mouth of the bag contained within the carton as it approaches the bag sealing and tucking mechanism.

This mechanism is best shown in Figures III, IV, V, VI, VII and VIII. As shown in Figure V each of a pair of adhesive applying blocks 54 are pivotally connected to the lower extremity of a pair of plunger rods 55 which are resiliently and slidably mounted within a hood 56. The hood 56 is rigidly secured to a longitudinally movable table 59 slidably mounted upon a pair of rods 60 which are rigidly affixed to a transversely movable table 61. The table 61 is slidably mounted upon a pair of rods 62 which are rigidly secured to the machine frame.

The tables 59 and 61, as well as the hood 56, are shown in their inoperative or retracted position in Fig. VII. These members are shown in their operative or extended position in Figure V. Suitable mechanism is provided for causing the hood 56 containing the adhesive applying blocks 54 to be extended outwardly over the pathway of the carton to be operated upon and for causing these parts to travel along the pathway that the package travels while adhesive is transferred to the inner surface of the mouth of the bag contained within the carton.

The adhesive applying mechanism including the blocks 54 is caused to move outwardly over the line of travel of the bag to be sealed and to move inwardly away from the bag by reason of the transverse movement of the table 61. Transverse movement is imparted to the table 61 by means of a pinion gear 64 carried upon a carriage 65 slidably mounted in a groove within a stationary frame of the machine. The pinion gear 64 meshes with the teeth of a stationary rack 66 on one side and the teeth of a rack 67 carried by the table 61 on the other side. The carriage 65 carrying the pinion gear 64 is moved in and out by means of a lever 68 rigidly secured to a rotatable shaft 63. A rotary movement is imparted to the shaft 63 by means of a reciprocating crank 69 having one extremity connected to the shaft 63 as indicated at 70 and the other extremity associated with a revolving gear 71 carried by the drive shaft 72. The extremity of the crank 69 associated with the gear 71 is preferably forked and receives power therefrom by means of a conventional raceway connection therewith.

As the carriage 65 is moved in and out by reason of the drive connections just described the pinion gear 64 causes the table 61 to move back and forth upon the rods 62 whereby the adhesive applying mechanism is alternately extended over the pathway of the moving package and withdrawn to an inoperative position.

The longitudinal movement of table 59 is accomplished in a manner substantially identical

to the transverse movement of the table 61. As best shown in Fig. V a movable carriage 73 is mounted upon a pair of slide rods 74 carried by the table 61. A pinion gear 75 is supported upon the carriage 73. Its teeth mesh at one side with the teeth of a rack 76 secured to the table 61 and on the other side with the teeth of a rack 77 secured to the table 59. A proper longitudinal movement is imparted to the carriage 73 by means of suitable connecting links 78, 80 and 10 lever 79. These links are actuated to movement by reason of their association with drive shaft 82 in the same manner that link 69 is associated with shaft 72. Shaft 82 is driven from shaft 72 by means of a drive chain 83. Chain 83 is held 15 taut by the chain tightener 83a.

From the foregoing description it will be apparent, since the adhesive blocks 54 and the mechanism associated therewith are secured to the table 59 which is in turn secured to table 61 that the blocks will move back and forth along the line of travel of the carrier members 31 while at the same time they will be alternately extended and retracted. These movements are properly timed so that the adhesive applying 20 mechanism will come into position over one of the carrier members 31, as shown in dotted lines in Figure VII, and thereafter travel with the carrier member for a short distance in the direction of the arrow in that figure.

As the hood 56 containing the adhesive applying mechanism moves along over the package carried by the carrier member 31 a roller 84 rigidly and rotatably secured to the upper extremity of the resiliently mounted rods 55 comes in contact at the proper instant with a movable cam 85 which has been actuated to contact the roller 84. The cam 85 is operated by means of the shafts 57 and 81 and the lever 58 all operatively connected together and deriving power from the 25 drive shaft 86.

When the cam 85 strikes the roller 84 the rods 55 are projected downwardly. The downward movement of the rods 55 cause the blocks 54 to assume the position shown in dotted lines in Figure V. In this manner adhesive is transferred from the blocks to the inside surface of the mouth of the bag forming a part of the package P. The blocks are actuated to move to this position by reason of their pivotal connection at 93 to shafts 91 secured to the lower extremity of rods 55. The blocks are also pivotally connected to a pair of links 88 which are in turn pivotally connected to a pair of stationary shafts 87. Accordingly, when the rods 55 cause the blocks 54 to move downwardly the restraining influence of the links 88 also causes them to rotate to the position shown in dotted lines in Figure V. The rods 55 and blocks 54 are normally held in the position shown in full lines in Figure V by means of a compression spring 92 encircling pin 93 and compressed between a stationary part of the hood and a part movable with the rods 55. As soon as the pressure of the cam 85 is released from the roller 84 the spring 92 causes the blocks 55 to resume their inoperative position. A set screw 18 limits the upward movement of the rods 55 and the blocks 54.

After adhesive has been applied to the inner surface of the mouth of the bag the adhesive applying mechanism is returned to its starting position by reason of the movement of the tables 59 and 61. In returning to their starting position the blocks 54 pass over a roller 94 partly immersed in a quantity of liquid adhesive con-

tained within a tank or container 95. The roller 94 is suitably mounted within the tank 95 so that it may be rotated by means of a chain or belt 96 operatively connected to the drive shaft 86, whereby to insure an even distribution of adhesive upon the blocks 54. It will, of course, be understood that the adhesive roller 94 is driven in the same direction and at the same speed as the blocks 54 at the time they contact therewith. Suitable mechanism, shown in Figure VI and identified by the numeral 97, is provided to prevent adhesive from accumulating in undesirable quantities upon the roller 94.

In order to prevent the adhesive applying blocks 54 from contacting the roller 94 as they move outwardly to apply adhesive upon the bags, suitable mechanism is provided for raising and lowering the tank 95 supporting the roller 94. This mechanism comprises the links 98, 100 and lever 99, 101, which are, as shown in Figure IV, actuated by means of their association at 102 with the rotating pulley 103 carried by the drive shaft 86. It will of course be understood that tank 95 and roller 94 are lowered but slightly to permit the blocks 54 to pass above the roller. A belt tightener 96a keeps belt 96 taut when roller 94 is lowered, thus preventing the belt from becoming disengaged from the roller 94 or the pulley carried by shaft 86.

In order to insure a proper sealing of the bag after applying adhesive to the inner surface of the side walls thereof, the ends of the bag are folded whereby the side walls are caused to assume substantially parallel positions in relatively close proximity to each other. This operation is accomplished by a pair of folding arms 104 and 105 which are pivotally connected to a bracket 106. The arms 104 and 105 are actuated to form a fold in the opposite ends of a bag by means of a pair of links 107 and 108 which are pivotally connected to a rod or shaft 110 supported by a bracket 109 carried by a frame member 111. The shaft 110 is oscillated by means of a pair of links 112 and 113 which are operatively associated in a well known manner with a pulley rigidly secured to the drive shaft 82.

It will be remembered that each of the carton flaps, with the exception of the rear flap, are held in a position at right angles to the body of the carton as it approaches the folding mechanism. In order to prevent the rear flap of the carton from interfering with the folding mechanism just described a flap retaining finger 114 is actuated through suitable connection with the shaft 110 to bend the rear flap of the carton away from the mouth of the bag temporarily while the folding mechanism is operating thereon.

After the end portions of the bag have been folded as just described the side portions are pressed together by a pair of presser irons 115. Each of these presser irons are supported by a longitudinally movable table 117 which is in turn supported by a transversely movable table 116. The longitudinally movable table 117 is mounted upon a pair of slide rods 118 rigidly secured to the table 116. The transversely movable table 116 is mounted upon a pair of slide rods 119 rigidly secured to the machine frame. Longitudinal movement is imparted to the table 117 by means of a pinion gear 120 operatively associated with a fixed rack and a rack carried by the table. The pinion gear is actuated to move the table 117 longitudinally by means of a link 121 connected to a shaft 122 which is oscillated by means of a thrust rod 123. The thrust rod 123 is opera-

tively associated with a cam 124 carried by a drive shaft 125. The transversely movable table 116 is actuated to move in and out by reason of its connection with an oscillating shaft 126 through means of a link 127 and an arm 128. An oscillatory movement is imparted to the shaft 126 by means of suitable motion transmitting mechanism 129 connected to the base of the shaft 126 and operatively associated with a cam member carried by the drive shaft 125.

It will be observed that only one of the shafts 126 is connected as just described with the drive shaft 125. Motion is transmitted to the other shaft 126 and in turn to the other transversely movable table 116 by means of a tie rod 131. In this manner the two opposed pressing irons 115 are moved longitudinally and transversely whereby to press the edges of the bag together while traveling with the same. The tie rod 131 insures proper cooperation between the opposing presser plates 115. A suitable resistance coil, not shown, may be associated with one of the presser plates 115 and connected with a source of electrical energy for the purpose of heating the plate, whereby to facilitate the sealing of the bag operated upon by the plates.

When heat is used in connection with the presser plates 115, it is desirable to retain the mouth of the bag in its closed or sealed position until cooled. When heat is not applied it is desirable to hold the mouth of the sealed or closed bag in a closed position until the adhesive has partially set. The mechanism for accomplishing these results comprises a pair of endless chains 132 and 133. The chains are mounted upon rollers secured to stub shafts 134 and are positioned closely together. The chains 132 and 133 are spaced at a proper height so that the closed neck of the bag passes between them and is firmly held in a closed position. The rollers carried by the shafts 134 are revolved, whereby to cause the chains to travel with the bag, by means of a suitable gear 135, secured to one of the shafts, meshing with a similar gear 136 secured to the end of a shaft 137. The shaft 137 is driven by the drive shaft 125 through means of a suitable chain or belt connection 138.

After the mouth of the bag contained within the carton has been properly sealed by the application of adhesive thereto and the pressing of the same together, it is then tucked into the carton so that the latter may be closed and sealed over the mouth of the bag. The tucking mechanism comprises a presser plate 139 carrying therebeneath a resilient member 140 adapted to engage the extended neck of the bag and, upon being properly actuated, to tuck the same into the carton. The presser plate is operatively connected to a movable carriage 193a carried by movable carriage 193b. The carriages are actuated by means of the drive shaft 141 through the driven shaft 142 to move the presser plate toward and along with each carrier 31. When the presser plate 139 is moved to a proper position over the package to be operated upon, a trigger 143 associated with the presser plate 139 strikes a stationary cam 144 thus causing the resilient member 140 to be depressed whereby the mouth of the bag is pressed down into the carton.

CHAPTER III

Carton closing and expelling mechanism

As described in Chapter II the mouth of the bag contained within the carton is sealed in a

closed position and tucked into the carton. Before the top of the carton can be closed over the bag, it is necessary to release the flaps from the restrained position they have occupied as heretofore described. Accordingly the rail 53, acting upon the finger 52 to hold the presser plate 51 against the forward flap, is discontinued whereupon the plate 51 releases the forward flap and returns to its inoperative position.

As soon as the forward flap has been released as just described, the carrier member 31 delivers the carton to a position where a runner or forward flap closing plate 145 is secured to a bracket 146. Also connected to the bracket 146 is a rear flap closing finger 146a adapted to raise the rear flap far enough to permit the upturned forward edge of the runner 145 to press it snugly against the top of the carton. A pitman 147 having a forked extremity engaging a cam 141a carried by shaft 141 actuates finger 146a through ratchet mechanism 146b to engage the rear flap at the proper moment.

Adjacent the mechanism just described one of the side flap retaining rails 46 is discontinued and the flap thus released passes between a pair of adhesive rollers 148 and 149 positioned alongside the carrier system. Roller 148 is partially immersed in an adhesive bath 150. It is rotated by roller 149 contacting therewith. Roller 149 is secured to rotatable shaft driven from one of the drive shafts of the machine by the chain 151.

Adjacent the glue applying mechanism the flap retaining rail 45 retaining the other flap is also discontinued and the guide rail 43 is continued in the form of a shield 152 by means of which that flap is gradually brought to an upright position preparatory to being closed.

After the side flap has been coated on both surfaces with adhesive, as just described, it is bent upwardly and inwardly by means of a stationary guide rod 153 while at the same time the opposite flap is being bent into a closed position over it by means of the guide plate 152. The glued flap is pressed down against the front and rear flaps by means of a roller 154 resiliently mounted upon a bracket 169 carried by the longitudinally movable carriage 155. Longitudinal movement is imparted to the carriage 155 in a well known manner by means of suitable pinion gear and rack mechanism 166. Power is delivered to the pinion gear from one of the drive shafts of the machine through means of the pitman 165. The longitudinally movable carriage 155 is mounted upon slide rods 167 carried by a transversely movable carriage 156 mounted upon slide rods 168.

The resilient mounting for roller 154 includes the springs 170 which tend to keep the roller in the extended position shown. The frame supporting the roller 154 carries a smaller roller 157 adapted to contact a stationary cam 158 whereby to contract springs 170 to hold roller 154 in a retracted position. When the carriage 155 is moved to the position shown roller 157 disengages cam 158 and springs 170 project roller 154 across the top of the package whereby the glued side flap of the carton is pressed down against the end flaps. Carriage 156 is moved toward the carton by the crank 159 secured to shaft 160. Shaft 160 is oscillated through suitable connection, not shown, with one of the drive shafts. This movement of carriage 156 causes a plate carried by bracket 169 to strike the carton. In this manner the carton is projected from its carriage 31 and at the same time the unglued side flap is pressed down upon the glued flap by the extended

portion 161 of the guide plate 152. When the carton is projected from the carriage 31 it is transferred to a bed 162 and passes under rollers 163 which continue the downward pressure upon the top flap. From the bed 161 the carton passes to a carrier belt 164.

5

Summary

The packaging machine herein shown and described as embodying the present invention is 10 designed to operate upon open-mouthed material containing bags disposed within open topped protective cartons. The bag and carton may be formed, and material may be placed in the bag, by a machine operated in combination with the 15 present machine. Likewise these operations may all be performed by the same machine that closes and seals the bag and carton.

However, material containing bags and cartons are delivered to the packaging machine here 20 shown by means of conveyor belt 20. The first operation performed upon them comprises arranging them upon the belt in properly spaced relation to each other. The material is then properly stowed in the bag by means of the 25 tamping block 28. The succeeding operations require the package comprising the bag and carton to be held firmly while being operated upon. Accordingly the package is next transferred to the individual carrier members 31.

30

After the package has been transferred to the individual carrier member 31 the spreader plates 39 act upon the mouth of the bag and the side flaps of the carton to deflect the latter outwardly and downwardly where they are engaged by the 35 flap retaining rails 45 and 46. At the same time the rotating finger 47 and arm 48 bend the forward carton flap away from the carton where it is engaged by the flap retaining plate 51 secured to the next preceding carriage 31. In this manner the side and forward carton flaps are moved away from the extended mouth of the bag where by the bag mouth-closing and sealing and tucking operations may be performed without interference from the carton flaps.

45

The mouth of the bag is closed and sealed by means of applying adhesive to the inner surface of the same and thereafter pressing the edges thereof together. Adhesive is applied to the mouth of each bag by the adhesive blocks 54 50 while travelling therewith. Between each successive application of adhesive the blocks 54 replenish their supply of adhesive by passing over the adhesive roller 94. After the inner surface of the mouth of the bag has been coated with adhesive the ends of the bag are folded by the folding arms 104 and 105 to bring the sides thereof in spaced parallel relation. During the folding operation the rear carton flap is pressed away from the mouth of the bag by the flap retaining 60 finger 114.

55

The substantially parallel side walls of the mouth of the bag are next firmly pressed together by the presser irons 115, one of which may be heated, whereby to cause the adhesive contained on the same to effectively seal the mouth of the bag. In order to assure a satisfactory sealing of the mouth it is next passed between the revolving chains 132 and 133 which hold it in a closed position while it is cooling and until the 70 adhesive has set sufficiently to eliminate the possibility of an imperfect sealing thereof. Immediately after the sealing operation the extended mouth of the bag is tucked down into the carton by the resilient tucking member 140.

65

70

75

The final operations upon the package consist of releasing the retained side and forward flaps of the carton, passing one of the side flaps between the adhesive rollers 148 and 149, folding 5 the end flaps upon the closed mouth of the bag by the plate 145, pressing the adhesive coated flap down upon the end flaps by means of the roller 154, folding the other side flap over the adhesive flap by means of the guide plate 152, 10 and ejecting the package from the machine by the plate secured to the movable carriage 155 whereby the package is forced beneath the rollers 163 which press the uncoated side flap firmly against the opposite adhesive coated side flap. 15 In this manner the carton is sealed in a closed position, and the package ejected from the machine and transferred to the conveyor belt 164.

It will, of course, be remembered that after a package has been transferred to the carriage 20 members 31 all of the succeeding operations are performed upon the package while it is being continuously moved by the endless chain 35. However, if desired, the motion of the chain, and accordingly the packages carried by the carriers 25 31, may be made intermittent, in which event slight changes would be made in the operating mechanism.

While only a single specific embodiment of the invention has been herein shown and described, 30 it should be understood that the invention is not limited thereto but is co-extensive with the scope of the appended claims.

We claim:

1. A bag sealing machine including in combination, means for carrying an open mouthed bag, means for applying adhesive to the inside edges of the mouth thereof at the same time, means for folding the mouth of the bag to form a pair of substantially parallel side walls, and 40 means for pressing the said pair of side walls together, whereby to seal the mouth.

2. A bag sealing machine including in combination, means for carrying an open mouthed bag, means for applying adhesive to the mouth 45 of the bag, means for folding the mouth of the bag to form a pair of substantially parallel side walls, and means for simultaneously applying pressure and heat to the outer surface of the said side walls, whereby to effectually seal the 50 mouth of the bag.

3. A bag sealing machine including in combination, means for carrying an open mouthed bag, means for applying adhesive to the mouth of the bag, means for simultaneously applying heat and pressure to the mouth of the bag to effectually seal the same, and means for cooling the mouth of the bag while retaining it under pressure.

4. A bag sealing machine including in combination, means for carrying an open mouthed bag, means for applying adhesive to the mouth of the bag, and means traveling with the bag for pressing the mouth together while applying heat thereto whereby to seal the same.

5. A bag sealing machine comprising a carrying system adapted to move an open mouthed bag, an adhesive applying device adapted to travel in the same direction as the bag and enter the mouth of the bag and transfer adhesive to the inner surface thereof, and means disposed on the opposite sides of the carrier system for pressing the mouth of the bag together whereby to seal the same.

6. A bag sealing machine comprising a carrier system adapted to move an open mouthed bag,

an adhesive applying device adapted to enter the mouth of the moving bag and transfer adhesive to the inner surface thereof, and means disposed on opposite sides of the carrier system for pressing the mouth of the bag together whereby to seal the same.

7. A bag sealing machine comprising a carrier system adapted to move an open mouthed bag, an adhesive applying device adapted to enter the mouth of the moving bag and transfer adhesive to the inner surface thereof, and means adapted to move with the bag for pressing the mouth together whereby to seal the same.

8. A bag sealing machine comprising a carrier system adapted to move an open mouthed bag, a container for liquid adhesive disposed adjacent the carrier system, an adhesive applying device adapted to travel in the same direction as the bag and transfer adhesive from the said container to the inner surface of the mouth of the bag, and means disposed on the opposite sides of the carrier system for pressing the mouth of the bag together whereby to seal the same.

9. A bag sealing machine comprising a carrier system adapted to move an open mouthed bag, a stationary adhesive container disposed adjacent the carrier system, a movable adhesive device adapted to transfer adhesive from the container to the inner surface of the mouth of the bag while traveling with the bag, and means for pressing the mouth of the bag together whereby to seal the same.

10. A bag sealing machine comprising a carrier system adapted to move a plurality of spaced apart open mouthed bags, an adhesive container disposed adjacent the carrier system, an adhesive applying device adapted to transfer adhesive to the mouth of each bag successively, and to take up more adhesive from the said container while traveling from one bag to the next successive bag.

11. A bag sealing machine comprising a carrier system adapted to move a plurality of spaced apart open mouthed bags, a liquid adhesive container disposed adjacent the carrier system, an adhesive roller adapted to rotate with a portion thereof immersed in the said liquid adhesive, and an adhesive applying device adapted to transfer adhesive to the mouth of each bag successively and to take up more adhesive from the said roller while traveling from one bag to the next succeeding bag.

12. A bag sealing machine comprising a carrier system adapted to move a plurality of spaced apart open mouthed bags, an adhesive applying device adapted to travel a limited distance with each bag, and means for causing the said adhesive applying device to enter the mouth of the bag whereby to apply adhesive to the inner surface thereof during a portion of its travel with the bag.

13. A bag sealing machine comprising a carrier system adapted to move a plurality of spaced apart open mouthed bags, a stationary adhesive container disposed adjacent the carrier system, an adhesive applying device disposed adjacent the carrier system, means for oscillating the adhesive applying device longitudinally and transversely of the carrier system whereby the said device travels a limited distance with each bag successively, means for actuating the adhesive applying device to enter the mouth of each bag while traveling with it whereby adhesive is transferred to the inner surface thereof, and means for replenishing the adhesive on the ad-

hesive applying device while returning to its starting position preparatory to traveling with the next succeeding bag.

14. A machine for sealing material in lined cartons including in combination, means for moving an open topped carton containing an open mouthed bag, adhesive applying mechanism adapted to transfer adhesive to the mouth of the bag while traveling with the same, means for applying pressure to the mouth of the bag to close and seal the same, and means for closing the top of the carton.

15. A machine for sealing material in lined cartons including in combination, means for moving a plurality of spaced apart open topped cartons containing open mouthed bags, adhesive applying mechanism adapted to transfer adhesive to the mouth of each successive bag while moving with the same, means adapted to travel with each bag successively for applying pressure to the mouth thereof to close the same, and means for closing the top of the carton.

16. A machine for sealing material in lined cartons including in combination, means for moving a plurality of spaced apart open topped cartons containing open mouthed bags, stationary means for holding the carton tops away from the mouth of the bags while they are being operated upon, adhesive applying mechanism adapted to transfer adhesive to the mouth of each bag successively while moving with the same, means adapted to travel with each bag successively for applying pressure to the mouth thereof to close and seal the same, and means for closing the top of the carton.

17. A machine for sealing material in lined cartons including in combination, means for moving an open topped carton containing an open mouthed bag, means adapted to travel in the same direction as the bag for applying adhesive to the mouth of the bag whereby to seal the same, means for tucking the closed mouth into the carton, and means for closing the top of the carton over the bag.

18. A machine for sealing material in lined cartons including in combination, means for moving an open topped carton containing an open mouthed bag, adhesive applying mechanism adapted to transfer adhesive to the mouth of the bag, means for closing the mouth under pressure while applying heat thereto, and means for closing the top of the carton over the mouth of the bag.

19. A sealing machine comprising a carrier system adapted to move an open mouthed container, an adhesive applying device movable transversely to the movement of the container, thence with the same and downwardly into the mouth of the moving container to transfer adhesive to the inner surface thereof, and means adapted to move with the container for pressing the mouth together whereby to seal the same.

20. A bag sealing machine comprising a carrier system adapted to move an open mouthed bag, an adhesive container disposed adjacent the carrier system, a movable adhesive device adapted to transfer adhesive from the container to the inner surface of the mouth of the bag while traveling therewith, and means for lowering the container when the adhesive device is moved into operative position to apply adhesive to the mouth of the bag.

21. A bag sealing machine comprising a carrier system adapted to move an open mouthed

bag, an adhesive container disposed adjacent the carrier system, a movable adhesive device adapted to transfer adhesive from the container to the inner surface of the mouth of the bag while traveling therewith, and means for lowering the container when the adhesive device is moved into operative position to apply adhesive to the mouth of the bag, and means for pressing the mouth of the bag together whereby to seal the same.

22. A bag sealing machine comprising means for supporting a bag, an adhesive container disposed adjacent said supporting means, an adhesive roller adapted to rotate with a portion thereof immersed in the adhesive contained within said container, an adhesive applying device adapted to transfer adhesive from the roller to the inner opposed surfaces of the mouth of the bag at the same time, and means for moving the adhesive container away from the adhesive applying device before the latter transfers the adhesive.

23. A bag sealing machine comprising a carrier system adapted to move a plurality of spaced apart open mouthed bags, an adhesive container disposed adjacent the carrier system, an adhesive applying device adapted to transfer adhesive to the mouth of each bag successively and take up more adhesive from the said container while traveling from one bag to the next successive bag, and means for moving the container clear of the adhesive applying device when the latter is operated to apply the adhesive.

24. A sealing machine comprising means for supporting a plurality of spaced apart open mouthed containers, an adhesive receptacle disposed adjacent said supporting means, an adhesive applying device disposed adjacent said supporting means, means for oscillating the adhesive applying device longitudinally and transversely of the supporting means, means for actuating the adhesive applying device to enter the mouth of each container in a manner whereby to transfer adhesive to the inner opposed walls of the mouth at the same time, and means for replenishing the adhesive on the adhesive applying device while returning to its starting position preparatory to traveling in a position whereby to apply adhesive to enter the container.

25. A bag sealing machine comprising a carrier system adapted to move a plurality of spaced apart open mouthed bags, an adhesive container disposed adjacent the carrier system, an adhesive applying device disposed adjacent the carrier system, means for oscillating the adhesive applying device longitudinally and transversely of the carrier system whereby the said device travels a limited distance with each bag successively, means for actuating the adhesive applying device to enter the mouth of each bag while traveling with it whereby adhesive is transferred to the inner surface thereof, means for replenishing the adhesive on the adhesive applying device while returning to its starting position preparatory to traveling with the next succeeding bag, and means for applying pressure to the mouth of the bag to close and seal the same.

26. A bag sealing machine comprising a carrier system adapted to move a plurality of spaced apart open mouthed bags, an adhesive container disposed adjacent the carrier system, an adhesive applying device disposed adjacent the carrier system, means for oscillating the adhesive applying device longitudinally and transversely of the carrier system whereby the said device travels a limited distance with each bag successively,

means for actuating the adhesive applying device to enter the mouth of each bag while traveling with it whereby adhesive is transferred to the inner surface thereof, means for moving the adhesive container clear of the adhesive applying device when the latter is actuated, means for replenishing the adhesive on the adhesive applying device while returning to its starting position preparatory to traveling with the next succeeding bag, and means for applying pressure to the mouth of the bag to close and seal the same.

27. A machine for sealing material in lined cartons including in combination means for moving a plurality of spaced apart open topped cartons containing open mouthed bags, adhesive applying mechanism adapted to transfer adhesive to the inner surface of the mouth of each successive bag, means adapted to travel at the same rate of speed as the bag for successively applying pressure to the mouth of each bag to close the same, and means for closing the top of the carton.

28. A bag sealing machine comprising a carrier system adapted to move an open mouthed bag, an adhesive applying device adapted to enter the mouth of the bag and transfer adhesive to the inner surface thereof, and means for pressing the sides of the moving bag together whereby to seal the same.

29. A bag sealing machine comprising a carrier system adapted to move a plurality of spaced

apart open mouthed bags, an adhesive device adapted to transfer adhesive to the mouth of each bag successively, means for replenishing the adhesive on the adhesive device between each successive application of adhesive to a bag, and means for applying pressure to the mouth of the moving bag whereby to seal the same.

30. A machine for sealing material in lined cartons including in combination means for moving an open topped carton containing an open mouthed bag, adhesive applying mechanism adapted to apply adhesive to the mouth of the moving bag, means for applying pressure to the mouth of the moving bag to close and seal the same, and means for closing the top of the carton over the closed mouth of the bag.

31. A machine for sealing material in lined cartons including in combination means for moving an open topped carton containing an open mouthed bag, adhesive applying mechanism adapted to transfer adhesive to the mouth of the bag, means for holding the top of the carton away from the mouth of the bag while adhesive is being applied thereto, means for applying pressure to the mouth of the bag to close and seal the same, and means for closing the top of the carton over the closed mouth of the bag.
